DESIGN FOR A COMBINED CIGARETTE
REST AND MATCH HOLDER

William L. Russo, Long Beach, and Frank McLaughlin, New York, N. Y.; said McLaughlin assignor to said Russo

Application April 27, 1946, Serial No. 129,017

Term of patent 7 years

(Cl. D85—2)

To all whom it may concern:

Be it known that we, William L. Russo and Frank McLaughlin, both citizens of the United States, residing in Long Beach, Nassau County, State of New York, and the city, county, and State of New York, respectively, have invented a new, original, and ornamental design for a Combined Cigarette Rest and Match Holder, of which the following is a specification, reference being had to the accompanying drawing, forming a part thereof, in which the figure is a perspective view of a combined cigarette rest and match holder, embodying our new design.

The side of the article opposite from that shown in the drawing follows the lines of the side illustrated therein.

We claim:

The ornamental design for a combined cigarette rest and match holder, as shown and described.

WILLIAM L. RUSSO.
FRANK McLAUGHLIN.
